UNITED STATES PATENT OFFICE.

FRANK P. HARDEN, OF BOSTON, MASSACHUSETTS.

DESIGN FOR A ROCKING-CHAIR.

SPECIFICATION forming part of Design No. 24,301, dated May 14, 1895.

Application filed April 11, 1895. Serial No. 545,401. Term of patent 7 years.

To all whom it may concern:

Be it known that I, FRANK P. HARDEN, a citizen of the United States, residing at Boston, in the county of Suffolk and State of Massachusetts, have invented and produced a new and original Design for Rocking-Chairs, of which the following is a specification, reference being had to the accompanying drawing.

My invention relates to a new design for 10 rocking chairs, and it consists in the unitary design as herewith shown.

In the accompanying drawing, which illustrates my invention, *a* represents the back which is rounded at its upper corners.

15 *b*, represents the seat and the sides *c*, extend vertically downward therefrom and are

provided with openings *d*. At the lower edges of the sides are the rockers *e*. The front *f* is also provided with an opening *g* and with downwardly extending curved arms or brackets *h*, which fit against the inner sides of the rockers.

The chair is formed entire of a thin material and presents a neat attractive appearance.

Having thus described my invention, I claim—

The design for a rocking chair, substantially as herein described and shown.

FRANK P. HARDEN.
